SOCK

Michael P. Rock, West Islip, N. Y., assignor to Murphy, Brill and Sahner, Incorporated, New York, N. Y., a corporation of New York

Application July 18, 1957, Serial No. 46,984

Term of patent 14 years

(Cl. D47—7)

The dominant feature of the design resides in the representation of the Colt .45 revolver on the sock as shown in the drawing. Part of the foot portion of the sock has been broken away for convenience of illustration.

I claim:

The ornamental design for a sock, substantially as shown and described.
